UNITED STATES PATENT OFFICE.

WILLIAM E. PRINDLE, OF LONDON, OHIO, ASSIGNOR TO THE BUCKEYE DRYER COMPANY,
OF COLUMBUS, OHIO, A CORPORATION.

DRIER.

1,321,332.

Specification of Letters Patent.

Patented Nov. 11, 1919.

Application filed April 30, 1917. Serial No. 165,317.

To all whom it may concern:

Be it known that I, WILLIAM E. PRINDLE, a citizen of the United States, residing at London, in the county of Madison and State 5 of Ohio, have invented certain new and useful Improvements in Driers, of which the following is a specification.

This invention relates to driers of the rotary type and is particularly directed to the 10 improvement of a rotary drier which may be used in extracting the moisture from pulp and similar moist materials. The invention consists essentially in the interior arrangement of parts for effectively removing 15 all of the moisture contained within the material, to thereby discharge from the drier a uniformly dry product.

To this end, my invention has for its 20 main object the arrangement of longitudinally extending compartments within the interior of the shell, which compartments gradually increase in number as the dry end of the shell is reached, so that a more thorough commingling of the products of 25 combustion with the pulp may be had.

Other objects of the invention become 30 more apparent after a further detailed description of the accompanying sheets of drawings, in which similar characters of reference designate corresponding parts, and in which:

Figure 1 is a view somewhat diagrammatic and showing the drier shell in section,

Fig. 2 is an enlarged section of the drier 35 shell shown detached,

Figs. 3 to 8 inclusive, are cross sections taken on lines 3—3, 4—4, 5—5, 6—6, 7—7 and 8—8 of Fig. 2, these sections being shown diagrammatically, and,

Fig. 9 is an enlarged cross section similar 40 to that shown in Fig. 3.

In carrying out my invention, I provide a tubular shell 1 which may be mounted upon tires 2 and rotated by means of the 45 gear mechanism 3 meshing with the annular spur gear 4, upon the shell itself. At the feed end of the shell, there is shown a furnace 5 which discharges its products of combustion into the interior of the shell. It is 50 into this front end that the material is introduced, preferably by means of a chute 6 embodied in or surrounded by a brick wall 7 to prevent the heat from burning it up. This material is gradually fed through the

shell, as are the products of combustion 55 from the furnace 5, the two finally entering the dust room or chamber 8. It will be understood that the discharge end of the shell opens into this dust room, but the products are prevented from direct passage therethrough by means of the baffles 9, 10 and 11. Most of the dried material drops to the bottom of this dust room and collects in the screw conveyer 12, but a portion may be drawn out through the pipe 13 which leads 60 to a fan or suction device 14. This latter discharges into the dust collector 15 whose discharge pipe 16 leads downwardly into a second conveyer 17. In this manner, all of the material is collected and that deposited 65 in the chamber 8 is fed to the conveyer 17 by means of the conveyer 12. This conveyer 17 in turn conveys the material to the boot 18 forming a portion of the elevator structure 19. This elevator may lead to any desired point and as is shown, is provided with a discharge spout 20 at its upper end. This discharge spout is arranged so that the material may be deposited through the leg 21, or it may be deposited upon the track conveyer 70 shown diagrammatically at 22. If the latter is the case, this track conveyer may be used to convey the material back to the feed end of the shell, this arrangement being re-sorted to in case the material is not thoroughly dried during its initial passage 75 through the shell. In this latter event, the material passes between the rake blades 23, through the spout 24 into the conveyer 25, from whence it is fed into the spout 26 80 which leads to the chute 6 already described. The spout 26 is provided with a door 27 which permits the direct placing of material into the shell, while the door 28 covers the conveyer 25 and it is through this that the 85 material is fed to the conveyer 25 to give a uniform flow through the drier shell.

The shell itself is composed of a plurality of sets of compartments 29, 30, 31, 32, 33 and 34. Each of these sets consists of four 100 compartments made by positioning plates 35 radially within the shell. Against the interior of the shell, are located spaced angles 36 within which the outer edges of the plates 35 may be slid, while the opposite 105 edges of these plates are held between pairs of angles 37 rigidly secured to the horizontal plates 35 as shown in Fig. 9. These

compartments are spaced from each other slightly and the front set 29 is provided with angular plates 38, which assist in forcing the material into the various compartments. These angular plates 38 are preferably set at about forty-five degrees and cooperate with the short spiral flights 39 located in the space 40 between the front set of compartments and the feed spout. Each 10 succeeding set of compartments to the rear of the set 29, have the front edges of their plates cut on an incline as is shown at 41, so that as the material is cascaded, it hits the projecting portion of these plates to 15 be in turn thereby fed into the various compartments. In addition to this, these edges 41 are also provided with angle members 42, whose outwardly projecting legs catch the material as it is cascaded to assist in the 20 feed thereof through the conveyer. The rear edges of each of these plates are also provided with an angle member 43 which serves merely in the capacity of a stiffener and in this manner coöperates with the angles 42, 25 which latter, in addition to the function already ascribed to them, also serve as stiffeners. Each of the plates 35 is provided with a series of lifting blades 44 slightly bent at their outer ends as shown at 45 and 30 bent at right angles at their inner ends as shown at 46 to be in turn riveted to the plates 35 as shown at 47. The numbers and sizes of these plates vary after the manner disclosed in Figs. 3 to 8 inclusive, from 35 which it will appear that as the material reaches the section 34, it is cascaded a great deal more than is the case when it is in the section 29. Also, the plates 35 in the sections 32, 33 and 34 are preferably perforated 40 to permit the sifting of any finely divided material therethrough, which would naturally be carried forward faster than the heavier particles, due to the movement which is caused by the passage of the products of 45 combustion therethrough. It is these dust particles particularly which are collected in the dust collector 15.

In the spaces formed between each set of compartments, there are located four short 50 lifting blades 48 preferably set at right angles to each other and these lifting blades are supplemented by those designated 49 in Figs. 3 and 4; 50 in Figs. 5 and 6, and 51 in Figs. 7 and 8. These latter lifting blades 55 49, 50 and 51 extend the entire distance between the front edge of the section 29 and the rear edge of the section 30; the front edge of the section 31 and the rear edge of the section 32; and the full length of each 60 of the sections 33 and 34 respectively. As will be seen by a comparison of Fig. 2 with Figs. 3 and 4, the blades 49 are located on the shell periphery within the various compartments and extend the full distance be-

tween the front edge of the sections 29 and 65 the rear edge of the section 30. This arrangement is followed through the remainder of the sections as is shown.

From the foregoing description, it will be apparent that, as the material is fed through the shell, it is gradually handled more and more so as to cause it to break up into finer particles and be subjected to the more intimate action of the heat carried by the products of combustion from the furnace. After 70 this material has passed through one compartment, it drops into the space formed between compartments and as it is cascaded in this space, it is gradually fed into the next succeeding compartment because of the 75 inclined front edge of the plates 35, this inclined edge being also supplemented by the angles 42. As this material passes rearwardly, it encounters more and more the lifting blades and finally, when it reaches 80 the section 32, it encounters the perforations in the plates 35. This permits any dust particles to fall through and during their drop, they will be naturally carried forward by the draft of the products of combustion. Finally, the entire mass of material is deposited in the dust room where, if it 85 has not become sufficiently dried, it may again be returned to the feed end of the drier and repassed therethrough.

In passing through the drier, the material is thoroughly mixed as well as dried. It will be understood that I have divided the spaces between the various sets of compartments, so that the material leaving all 100 of the compartments of one set will fall into the space between sets and become thoroughly mixed before again being subdivided into the next succeeding sets of compartments. In this manner, the same material 105 does not remain intact in its complete passage through the drier. This arrangement insures a more uniform drying of the entire mass.

What I claim, is:

1. In a rotary drier, a drier shell, and a plurality of longitudinally extending sets of compartments formed therein, said sets being spaced from each other lengthwise of the shell and lifting blades in such compartments, said blades increasing in number from the wet to the dry end of said shell.

2. In a rotary drier, a drier shell, and a plurality of longitudinally extending sets of compartments formed therein, said sets being slightly spaced from each other in the direction of length of said shell.

3. In a rotary drier, a drier shell, a plurality of longitudinally extending sets of compartments formed therein, said sets being slightly spaced from each other in the direction of length of said shell, and lifting

blades located on the periphery of said shell and in the spaces between said sets of compartments.

4. In a rotary drier, a drier shell, and a plurality of longitudinally extending sets of compartments therein formed of radially arranged division plates arranged to join at the center of said shell, said sets being spaced from each other lengthwise of the shell.

5. In a rotary drier, a drier shell, and a plurality of longitudinally extending sets of compartments therein formed of radially arranged division plates arranged to join at the center of said shell, each compartment being also provided with lifting blades, the number of blades in such compartments increasing from the wet to the dry end of said shell.

6. In a rotary drier, a drier shell, and a plurality of longitudinally extending sets of compartments therein formed from radially positioned plates, the front edges of said plates being cut on angle so that they extend farther forward within the shell as they approach the center of the shell.

7. In a rotary drier, a drier shell, and a plurality of longitudinally extending sets

of compartments therein formed from radially positioned plates, the front edges of said plates being cut on an angle so that they extend farther forward within the shell as they approach the center of the shell, said inclined edges being also provided with an angular member to assist in drawing the material into said compartments.

8. In a rotary drier, a drier shell, a plurality of longitudinally extending sets of compartments therein formed from radially positioned plates, certain of said plates being also perforated, and lifting blades formed in said compartments.

9. In a drier mechanism, a rotatable shell, means for feeding material into said shell, means for passing heated gases through said shell, an elevator at the discharge end of said shell, and a horizontal conveyer leading from said elevator to the feed means for said shell.

In testimony whereof I affix my signature in presence of two witnesses.

WILLIAM E. PRINDLE.
